US0D1015409S

(12) **United States Design Patent** (10) **Patent No.:** **US D1,015,409 S**
(45) **Date of Patent:** **** Feb. 20, 2024**

(54) **SWIM GOGGLE CONNECTORS AND HEADBAND**

(71) Applicant: **Ashley Carson**, Goodyear, AZ (US)

(72) Inventor: **Ashley Carson**, Goodyear, AZ (US)

(73) Assignee: **Splash Biz, LLC**, Avondale, AZ (US)

(**) Term: **15 Years**

(21) Appl. No.: **29/652,889**

(22) Filed: **Dec. 30, 2020**

(51) **LOC (14) Cl.** **16-06**

(52) **U.S. Cl.**

USPC **D16/311**

(58) **Field of Classification Search**

USPC D16/309, 311, 330, 339, 340, 341, 323,
D16/337; D24/110.2; D29/109–110
CPC G02C 3/00; G02C 3/003; G02C 3/006;
G02C 3/02

(57) **CLAIM**

The ornamental design for a swim goggle connectors and headband, as shown and described.

DESCRIPTION

FIG. 1 is a top front perspective view of the swim goggle connectors and headband;

FIG. 2 is a front elevation view thereof;

FIG. 3 is a rear elevation view thereof, shown in an exploded view for visibility of the swim goggle connectors;

FIG. 4 is a right elevation view thereof, with the left elevation view being a mirror image thereof;

FIG. 5 is a top plan view swim goggle connector and headband, with the bottom plan view being a mirror image thereof; and,

FIG. 6 is a top front perspective view swim goggle connector and headband with the strap installed on the connectors. The broken lines shown in the drawings illustrate portions of the swim goggle connectors and headband that form no part of the claimed design.

1 Claim, 4 Drawing Sheets
